CLAIM

USPC D27/102, 136, 137, 163, 167, 172, 173,

I claim the ornamental design for a case for electronic
cigarette, as shown and described.

D27/174, 175, 176, 177, 178, 179, 180,
D27/181, 182, 183, 184, 185, 186, 187,
D27/188, 189, 190, 191, 192, 193, 194,
D27/195, 196; D11/184; D28/73, 74,
D28/76, 78, 83

DESCRIPTION

CPC A24F 47/008; A24F 15/18; A24F 15/12;

FIG. 1 is a bottom, front, right side perspective view of a
case for electronic cigarette, showing my new design;

A24F 15/20; A24F 47/002; A24F 15/00;

FIG. 2 is a top, front, right side perspective view thereof;

A24F 15/14; A24F 15/10; A24F 15/01;

FIG. 3 is a front elevational view thereof;

A24F 15/08; A24F 40/40; A24F 15/005;

FIG. 4 is a rear elevational view thereof;

A24F 15/02; A24F 21/00; A24F 40/95;

FIG. 5 is a left side elevational view thereof;

A24F 47/00; A24F 9/04; B65D 85/70;

FIG. 6 is a right side elevational view thereof;

B65D 25/108; B65D 43/16; B65D 25/10;

FIG. 7 is a top plan view thereof; and,

B65D 85/10; B65D 43/22; B65D 85/20;

FIG. 8 is a bottom plan view thereof.

B65D 2203/02; B65D 25/00; B65D

(Continued)

25/34; B65D 43/14; B65D 43/163; B65D

43/165; B65D 43/18; B65D 43/24; B65D

The broken lines in the drawings depict portions of the case for electronic cigarette which form no part of the claimed design.
